(57) **CLAIM**

The ornamental design for a underhood work light, as shown and described.

DESCRIPTION

FIG. 1 is a top perspective view of a first embodiment of an underhood work light embodying our new design; FIG. 2 is a bottom perspective view of the underhood work light of FIG. 1;

FIG. 3 is a perspective view of a first alternate configuration of the underhood work light of FIG. 1;

FIG. 4 is a perspective view of a second alternate configuration of the underhood work light of FIG. 1;

FIG. 5 is a top view of the underhood work light of FIG. 1; FIG. 6 is a bottom view of the underhood work light of FIG. 1;

FIG. 7 is a right-side view of the underhood work light of FIG. 1, the left-side being a mirror-image thereof and therefore not shown;

FIG. 8 is a front view of the underhood work light of FIG. 1, the rear view being a mirror-image thereof and therefore not shown;

FIG. 9 is a top perspective view of a third embodiment of an underhood work light embodying our new design;

FIG. 10 is a bottom perspective view of the underhood work light of FIG. 9;

FIG. 11 is a perspective view of a first alternate configuration of the underhood work light of FIG. 9;

FIG. 12 is a perspective view of a second alternate configuration of the underhood work light of FIG. 9;

FIG. 13 of the underhood work light of FIG. 9;

FIG. 14 is a bottom view of the underhood work light of FIG. 9;

FIG. 15 is a right-side view of the underhood work light of FIG. 9, the left-side being a mirror-image thereof and therefore not shown; and,

FIG. 16 is a front view of the underhood work light of FIG. 9, the rear view being a mirror-image thereof and therefore not shown.

The broken lines show portions of the underhood work light not claimed and form no part of the claimed design.
